COSMETIC PENCIL HOLDER

Charles M. Tursky, Englewood, N. J.

Application September 17, 1946, Serial No. 697,549

2 Claims. (Cl. 206—56)

1

This invention relates generally to holders for cosmetics in the form of bars and rods, but more specifically to a holder having mechanical means for ejecting and retracting the cosmetic from and within an enclosed protective chamber.

The main object of the invention resides in the provision of a holder for cosmetic bars and rods which is provided with means for ejecting and retracting the cosmetic from and within a chamber for respective operative and closure purposes, the chamber normally having a closure device which is openable by the propulsion therethrough of the chamber walls containing the cosmetic.

A further object of the invention resides in the provision of a cosmetic pencil holder having a propellable socket for the pencil and a covering chamber provided with a closure device which is openable upon projection therethrough of the socket and springably closable by the retraction of the socket therefrom.

A further object of the invention resides in the provision of a cosmetic pencil holder having a propellable socket for the cosmetic pencil and wherein mechanical means are provided to adjust the position of the pencil within the socket.

Another object of the invention resides in the provision of a cosmetic pencil holder of the above nature which may be easily assembled and dismantled and which comprises a minimum number of parts which are economical to manufacture and which cooperate with each other with facility and without possibility of relative jamming to impair proper operation.

A further object of the invention resides in the provision of a cosmetic pencil holder which is aesthetic and graceful in appearance, positive in action and sufficiently compact to be carried within the purse or bag of the user.

These objects and other incidental ends and advantages of the invention will hereinafter appear in the progress of the disclosure and as pointed out in the appended claims.

Accompanying this specification are drawings showing preferred forms of the invention wherein corresponding reference characters designate corresponding parts and wherein:

Figure 1 is an axial sectional view of the propellable cosmetic pencil holder in closed position.

Figure 2 is an axial sectional view of the holder shown in Figure 1 in open position.

Figure 3 is a view in elevation of the device shown in Figure 1.

Figure 4 is a front end view in elevation of Figure 3.

In Figures 1-4 a cosmetic holder is shown of

2

the push-pull type which embodies the features of the present invention.

A shell socket 28 containing the cosmetic or lipstick 16e is reciprocable by an inward push and an outward pull of an extension which is in slidable engagement with the inner face of an outer casing. The closure device for the socket is adapted to be movably secured between said casing and the shell socket and operative upon 10 by the tapered wall of the outer edge of the shell socket.

The outer casing is comprised of a shell 23 reduced and threaded at the ends thereof as at 24 and 25 to threadedly and respectively engage an 15 adapter 26 for the closure device and a cap 27. The shell socket 28 containing the cosmetic 16e is adapted to be axially pushed and pulled through and from the closure device for operation thereof and for this purpose, a socket extension 29 is provided upon which the operating force is exerted. As shown the external diameter of socket extension 29 is greater than the external diameter of socket 28. Between socket 28 and extension 29 is an externally expanded cylindrical portion 30 which is adapted to bear against and be in slidable engagement with the inner wall of the tubular shell 23 of the outer casing.

Cylindrical portion 30 has an inner and outer peripheral shoulder 31 and 32 respectively. Cap 30 35 has a reduced cylindrical bore portion 33 and serves as a bearing surface for extension 29, the said bore portion 33 forming a shoulder 34 to serve as a stop for shoulder 31 of cylindrical portion 30 of shell 28 for limiting retracted position 35 of socket 28.

The socket 28 at the outer end is provided with a tapered or conically shaped outer wall 35 which is adapted to cause a displacement of blades 15 when the socket 28 is caused to be pushed forwardly of shell 23 and which causes retraction of the blades 15 when the socket is pulled from shell 23. The blades 15 constituting the closure device for the socket 28 are constructed similarly to that shown in the first embodiment of the invention except that the flared necks 15b shown in Figures 1-5 are divided into a flared portion 15b' and a straight portion 35'. The straight portion 35'' of each of the blades 15 is provided with an outwardly turned leg 15a which is maintained between an inwardly extending peripheral flange 26a having a bevel 26a' on the outer edge of adapter 26 and a ring 36. Ring 36 is yieldably held in place by means of a coiled spring 37 which is seated on another ring 38 held against the outer 50 edge of casement shell 23.

A piston head 39 slidable within the socket 28 is adapted to serve as the bottom supporting wall for the cosmetic pencil 16e within the socket, the said piston head having an externally threaded hollow stem 40 which is in threaded engagement with a sleeve 41 therefor within socket extension 29. The end portion of sleeve 41 terminates in a square shaped bore 41a and an external peripheral flange 42. Flange 42 abuts against the inner edge of socket extension 29 and the inner end of cap 27 in limiting projected position of socket 28 while a tubular stem member 43 is freely mounted within the bore of piston head stem 40. Stem 43 adjacent the end has an expanded square shaped shoulder 43a which engages with the square shaped bore 41a of sleeve 41, said shoulder 43a terminating in a knob 44 which engages the sleeve end 45.

Between the surface of shoulder 43a and a groove 46 on the inner wall of flange 42 is a spring 47 which serves to offer frictional resistance to prevent easy withdrawal of stem 43 from piston stem 40. Stem 43 may be used as a socket for an eyebrow pencil and the like and is withdrawable by outward hand pressure on knob 44.

On the outer surface of sleeve 41 adjacent the flange 42 is a groove 48 which is opposed to another groove 49 situated on the inner wall of socket 29 the said grooves together forming a runway for a circular spring 50. The purpose of spring 50 is to prevent easy separation between sleeve 41 and socket 29, the parts being separable by exertion of extra force for assemblage and disassemblage of the device. When it is desired to further project lipstick 16e beyond the end of socket 28 when socket 28 is in projected position, flange 42 is rotated, the extension 29 being prevented from rotation by the gripping action of blades 15 on socket 28 when the blades are in open position.

The piston head 39 is provided with a groove 51 along the peripheral wall to receive a spring 52 which bears against the inner wall of the socket 28 and the function of spring 52 is to prevent rotation of the piston head 39 and piston stem 40 with the rotation of sleeve 41 when flange 42 is rotated for projection of the lipstick 16e.

To disassemble the device cap 27 is unscrewed from the end of shell 23 whereupon shell 23, adapter 26, the closure device and mounting therefor are all removable as a unit from socket 28. This unit when removed may be further broken down by unscrewing adapter 26 from shell 23 whereupon the blades 15, disks or rings 36 and 38 of the spring 37 are separated. Sleeve 41 carrying piston stem 40 and the cosmetic stem 43 is removable from socket extension 29 by exerting a pull on flange 42 against the force of spring 52 whereupon piston stem 40 may be unscrewed from sleeve 41.

I wish it understood that the cosmetic holder as above described may be modified in respect to the size, shape, location, material, integration and combination of parts without departing from the spirit of the invention and the scope of the appended claims.

I claim:

1. A cosmetic pencil holder comprising a shell socket adapted to contain a lipstick mass, said shell socket having an extension thereon, an internally threaded sleeve journaled in the exten-

sion, and locked against axial displacement therefrom, said internally threaded sleeve within the extension having an external peripheral flange at the end of the extension to effect the turning of the internally threaded sleeve, a piston head adjustable in the socket and having an externally threaded shank engaging with the threads of the internally threaded sleeve whereby as the flange of the internally threaded sleeve is adjusted the piston head can be extended or extracted whereby to extend the lipstick material from the outer end of the socket, said socket and extension having an intermediate portion providing shoulders, a sliding outer shell surrounding this socket and the extension and slidable thereupon, an adapter and a cap provided on the outer ends of the sliding shell, said cap having an abutment engageable with one of the shoulders to limit the outward movement of the shell over the socket, said adapter having an inwardly extending flange at the outer end thereof, covering blades for the end of the lipstick having formations extending into the adapter whereby said blades can be drawn over the socket by the sliding shell and separated from one another, spring means in the adapter acting upon the flanged ends of the blades for maintaining the same against the flange of the adapter and outwardly of the adapter, said socket having a conically shaped end face for effecting the spreading of the blades as the slide and the blades are pulled rearwardly over the socket, said adapter spring means engageable with the other shoulder of the socket portion to limit the rearward movement of the slide shell over the socket and the extension whereby as the slide shell is worked upon the socket shell and the extension the blades can be opened or closed over the end of the socket.

2. A cosmetic pencil holder as defined in claim 1 and a tubular stem member having a square portion and a knob, said tubular stem member insertible through the flanged end of the internally threaded sleeve and the hollow stem of the piston, said internally threaded sleeve having a square opening receiving the squared portion of the tubular stem member, said tubular stem member adapted to retain an eyebrow pencil and removable from the internally threaded sleeve and the piston stem for use by the owner of the pencil holder.

CHARLES M. TURSKY.
